CLAIM

The ornamental design for an injector for spray coating device, as shown and described.

DESCRIPTION

FIG. 1 is a front view of the injector, wherein a rear view of the injector is a mirror image of the front view.

FIG. 2 is a bottom view of the injector of FIG. 1.

FIG. 3 is a further bottom view of the injector of FIG. 1, as seen in the direction of arrow A in FIG. 1.

FIG. 4 is a left view of the injector of FIG. 1.

FIG. 5 is a top view of the injector of FIG. 1.

FIG. 6 is a right view of the injector of FIG. 1.

FIG. 7 is a rear-top-left perspective view of the injector of FIG. 1.

FIG. 8 is a front-top-right perspective view of the injector of FIG. 1.

FIG. 9 is a right, elevational, perspective view of the injector of FIG. 1; and,

FIG. 10 is a front view similar to FIG. 1, with a partial cross-section, showing the injector in an assembled state in which the injector is connected to two hoses on the top and a nozzle at the front. The hoses and the nozzle are shown in broken lines and form no part of the first embodiment of the design.

The broken lines in the drawings form no part of the claimed design.
